UNITED STATES PATENT OFFICE.

FAUSTO A. MUSCENTE, OF PROVIDENCE, RHODE ISLAND.

FLAPPING-SHOE-ORNAMENT HOLDER.

Application filed November 13, 1926. Serial No. 148,209.

This invention relates to ornament holders for shoes and has more particular reference to and for its primary object the provision of means whereby ornaments or various designs of buckles may be applied to the instep portion of a woman's slipper or pump, in such a manner as to cause the said ornament or buckle to "flap" or swing up and down and thus considerably enhance the appearance of the same.

One of the most important objects of the invention is to provide an article of the character wherein the ornament or buckle may be applied to the shoe without requiring the necessity of stitching or otherwise securing the ornament directly to the shoe and without the ornament or buckle contacting with the wearer's stocking which is the great disadvantage in the application of ornaments or buckles to said slippers or pumps.

An additional object is to provide an ornament of this character that may be readily attached or removed from the shoe and that when once applied will be maintained in permanent association with the shoe when the same is upon the foot of the wearer.

Other objects and advantages of the invention will become apparent from the following description taken in connection with the accompanying drawing:

In the drawing wherein like numerals indicate like parts throughout the several views:

Figure 1 is a perspective view of a conventional slipper or pump for women equipped with an ornament constructed in accordance with the present invention.

Fig. 2 is a front elevation of the ornament per se.

Fig. 3 is a perspective of one form of the attaching means for the ornament.

Fig. 4 is a perspective view of one form of ornament that may be used.

Fig. 5 is a detail section taken substantially upon the line 5—5 of Fig. 2, with the attaching means as shown in Fig. 3.

Fig. 6 is a group perspective of a two part attaching means for the ornament in distinction to a one part attaching means as disclosed more clearly in Fig. 3, and

Fig. 7 is a detail longitudinal sectional view thereof.

Now having particular reference to the drawing wherein there is disclosed two

forms of means whereby buckles or ornaments may be attached to low shoes, the first form of the invention disclosed in Figs. 1 to 5 inclusive, constitutes the provision of a strip of fabric or other suitable material designated by the numeral 5, upon one end of which is formed a turned over tab 6, preferably of a formation similar to the contour of the ornament or buckle to be attached as disclosed clearly in Figs. 2 and 3. The material constituting the strip at the connecting portion between the main body 5 and tab 6 is preferably of tapered formation as disclosed.

A suitable ornament or buckle, an ornament being shown in the drawing, and being designated by the reference character 7, is then secured to the outer face of the tab 6, preferably by stitching 8. The various stitching between the top side of the ornament 7 and the tab 6 preferably extends through the body 5 directly at the connecting portion of the material between said body and said tab, as disclosed in Fig. 5. This will limit the upward swinging movement of the ornament carrying tab after the article has been applied to the shoe as indicated in Fig. 1.

In actual practice, the body 5 is arranged on the inner side of the shoe 8 at the instep portion thereof, the ornament carrying tab 6 being disposed upon the outer side of the instep portion as clearly disclosed in said Fig. 1. When the shoe is applied to the foot, the body 5 will be securely bound between the shoe and the foot of the wearer so as to prevent the slippage of the ornament with respect to the shoe.

When the foot is in movement, the tab will flap or swing to certain degree and consequently the ornaments will be more readily visible to passers-by.

In the form of the invention disclosed in Figs. 6 and 7, the attaching means consists of a separate body 5' and tab 6', but may be stitched together at their upper edges as clearly disclosed in Fig. 7. In this instance, also, the tab 6' is similar in contour to the contour of the ornament or buckle to be applied thereto, said ornament or buckle being secured to the tab in a manner, similar to that disclosed in Fig. 2. However, I do not desire to be limited to any form of attaching means for the buckle with respect to the tab.

It will thus be seen that I have provided highly novel, simple and efficient forms of shoe ornament or buckle holders that are well adapted for all of the purposes heretofore designated and even though I have herein shown and described the invention, as consisting of certain detail structural elements, it is nevertheless to be understood that some changes may be made therein without affecting the spirit and scope of the appended claims.

Having thus described my invention, what I claim as new is:—

1. In an article of the character described, a strip of fabric of predetermined length, an integral tab formed upon one end of the fabric strip and turned downwardly with respect thereto in such a manner as to enable said tab to flap or swing up and down, said strip of fabric adapted for disposition between the foot of a shoe wearer and the instep portion of the shoe while said tab is adapted for disposition upon the outer side of the shoe instep portion, an ornament arranged upon the outer side of the said tab and securing means between said ornament and said tab, said securing means passing through the tab and said strip of fabric at

the connecting point between said fabric and said tab.

2. In an article of the class described, a backing strip for disposition between the foot of a shoe wearer and the instep portion of the shoe, a downwardly extending tab carried by the upper end of the strip for engagement upon the outer side of the shoe, an ornament attached to the tab, and a flexible connection between the backing strip and the tab, whereby swinging movement of the tab and the ornament carried thereby is permitted.

3. In an article of the class described, an elongated backing strip of flexible textile material for disposition between the foot of a shoe wearer and the instep portion of the shoe, a tab of the same material, a flexible connection between the tab and the upper edge of the backing strip, said tab adapted for engagement upon the outside of the instep portion of the shoe, the flexible connection permitting the swinging movement of the tab.

In testimony whereof I affix my signature.

FAUSTO A. MUSCENTE.
